UNITED STATES PATENT OFFICE.

WALTER F. HEROLD, OF NEWARK, NEW JERSEY, ASSIGNOR TO THE BASSICK COMPANY, OF BRIDGEPORT, CONNECTICUT, A CORPORATION OF CONNECTICUT.

CASTER.

1,418,711.

Specification of Letters Patent. Patented June 6, 1922.

Application filed August 4, 1921. Serial No. 489,686.

To all whom it may concern:

Be it known that I, WALTER F. HEROLD, a citizen of the United States, and a resident of Newark, in the county of Essex and State 5 of New Jersey, have invented certain new and useful Improvements in Casters, of which the following is a specification.

The invention relates to casters, and particularly to casters intended for use with 10 furniture having hollow tapered legs. An object of the invention is the provision of a caster construction in which a retaining frame is arranged to firmly engage within the interior of a tapered leg, to hold the 15 caster in upright position at all times, even when used with a leg having a considerable taper from front to back and from side to side.

I accomplish this result by the provision 20 of a frame, preferably of spring metal, having side arms which are bent or twisted in such a manner that the top transverse portion of the frame may be positioned to extend diagonally across the interior of the 25 leg, while the bottom edges of the arms will engage against the interior of the leg adjacent the bottom thereof. With such an arrangement the transverse top portion of the frame, preferably rectangular, may be inserted 30 through a rectangular opening at the bottom of the leg, and the frame turned about its axis as it is pushed up, until it comes to its final position in which the top portion extends diagonally across the opening, 35 with all four corners engaging the sides of the opening, while side edges of the arms may engage opposite walls throughout their length.

Other objects of the invention comprise 40 the provision of improved details of construction and combinations of parts, as will appear more fully in the accompanying specification, and be particularly pointed out in the appended claims.

In order that the invention may be more 45 clearly understood attention is hereby directed to the accompanying drawings forming part of this application and illustrating, by way of example, one embodiment of the 50 invention. In the drawings,

Fig. 1 represents a side elevation of a 105 caster comprising the invention;

Fig. 2 is a front elevation of the same;

Fig. 3 is a top plan view of the same;

Fig. 4 is a side elevation of the caster as 55 the same is positioned at the beginning of its insertion into a tapered furniture leg; the leg being partly shown in cross section;

Fig. 5 is a horizontal section taken on line 5-5 of Fig. 4; 60

Fig. 6 is a view similar to that shown in Fig. 4, the caster being fully inserted into the furniture leg; and

Fig. 7 is a section taken on line 7-7 of Fig. 6. 65

Referring to the drawings, the caster may comprise the usual horn 1 carrying a caster wheel 2, or the like. In the form of construction illustrated the pintle 3 extends upwardly from the top transverse portion of horn 1, the leg supporting plate 4 being positioned in rotatable position on a shoulder 5 on pintle 3 above horn 1, the plate 4 being provided with a central opening therethrough through which the pintle extends. Plate 4 70 is preferably provided with upturned flanges 6 at or adjacent to its edges. 75

The spring frame, or more broadly speaking, the frame or member by which the 80 caster is retained in position when inserted in a furniture leg, is a frame, preferably formed of spring metal and having a transverse top portion 7 and arms 8, 8, at the sides. In the form of construction shown the transverse top portion 7 of the frame is provided 85 with a central opening therethrough through which pintle 3 extends, the upper portion of the pintle being upset, as indicated at 9, above the top portion 7 of the frame, so as to prevent the frame from slipping 90 off of the upper end of the pintle.

The present invention consists chiefly in the form of the frame referred to and it is not essential to the invention that the frame should be used in connection with a pintle 95 in the manner indicated, or that any particular form of member should be used for centering the frame and retaining the same in position above the leg supporting plate. In the construction shown the frame is centered and held in position by having the pintle extend through the top transverse portion 7 of the frame, the arms 8 extending downwardly on opposite sides from top portion 7 and having their lower edges engage 100 within the opposite flanges 6 of leg supporting plate 4, when the caster is not positioned in a furniture leg. The frame is preferably 105

formed from an integral strip of metal the side edges of which are parallel with each other.

The side arms 8 of the frame are bent or twisted in such a manner that the lower edges thereof are positioned in planes which extend at angles to the upper edges of the arms, the upper edges of the arms referred to being the side edges 10, 10, of the top portion 7 of the spring frame, this top portion preferably being approximately rectangular, as shown. The arms 8 are bent or twisted in such a manner that the lower edges thereof may contact against the inner surfaces of flanges 6 while the upper edges of the arms, that is the edges 10, 10, of the top portion 7 of the spring frame, extend at angles, which may be approximately angles of 45 degrees, to the planes in which the flanges 6 engaged by the lower ends of the arms extend.

To produce the desired effect the arms 8 are preferably bent or twisted in what is in effect a spiral curve, that is the arms 8 may be bent to give the same a form similar to that of the flutings of a spiral drill.

With such a construction the caster may be inserted within a tapered furniture leg, the interior of which is of rectangular section, in the manner indicated in Figs. 4 and 5. The lower end of the tapered leg 11 having a rectangular opening at the bottom somewhat larger in each direction than the top portion 7 of the spring frame, the caster is inserted within the leg with the side edges of top portion 7 of the spring frame parallel to the side walls of the leg. As the caster is pushed upwardly into the leg it will be turned somewhat about its axis, as if it were a screw being screwed into a threaded opening, this turning motion being necessary, on account of the inclination of arms 8, to enable the spring frame to be pushed up into the opening.

45 When the caster has been pushed all the way into its operative position, as shown in Figs. 6 and 7, the four corners 12 of the top portion 7 of the spring frame will engage against the four side walls of the interior of the leg while the lower edges 13, 13, of the side arms 8 engage against opposite interior walls of the furniture leg adjacent the bottom thereof, the furniture leg then resting on plate 4 with flanges 6 of plate 4 extending around the lower end portions of the leg.

When the caster is thus positioned it will be firmly held in place by the engagement of the four upper corners of the spring frame within the leg, by the engagement of the lower edges 13 within the leg and also by the engagement of side edges 14 of arms 8, from top to bottom thereof, with the corresponding interior surfaces of the leg. It will be noted that a plane may be extended

through and parallel with one of the lower edges 13 of an arm 8, this plane extending through the corner 12 of top portion 7 above the same and that this plane will include the side edge 14 of the arm 8 referred to. That is to say, a plane in which the lower edge 13 and the upwardly extending side edge 14 are both included or positioned, will be tangential to a circle the diameter of which is a diagonal of the top portion 7 of the frame.

The distance from side to side within the leg at the point at which corners 12 of top portion 7 of the frame engage is, of course, greater than the distance from side to side across the opening at the bottom of the leg through which the spring frame 8 was inserted, and it would be impossible to cause the top portion 7 of the frame to enter the opening at the bottom of the leg unless the frame were positioned as stated with its edges more or less parallel to the sides of the opening, the caster being turned about its axis as it is pushed up into position. It will be obvious that the construction described gives a firm bearing for the caster under various conditions of use even when the leg is one having a considerable taper.

It should be understood that the invention is not limited strictly to the details of construction described but is as broad as is indicated by the accompanying claims.

What I claim is:

1. In a caster, the combination of a leg-supporting plate, a frame comprising a transverse top portion and arms at opposite sides thereof, and means for holding said frame above said plate, said arms comprising spirally-bent metal strips.

2. In a caster, the combination of a leg-supporting plate, a frame comprising a transverse top portion and arms at opposite sides thereof, and means for holding said frame above said plate, said frame comprising a metal strip the transverse portion of which is rectangular, while the arms are twisted to position the lower edges thereof in planes which extend at angles to the upper edges thereof.

3. In a caster, the combination of a leg-supporting plate, a frame comprising a transverse top portion and arms at opposite sides thereof, and means for holding said frame above said plate, said top portion being rectangular and said arms being so bent that a plane extending through the lower edge of either arm and including a side edge of the arm will be tangential to a circle the diameter of which is a diagonal of said top portion.

4. In a caster, the combination of a leg-supporting plate, a frame comprising a transverse top portion and arms at opposite sides thereof, and means for holding said frame above said plate, said top portion being rectangular and said arms being

bent outwardly and laterally in such a manner that opposite corners of said top portion will be adapted to engage against opposite interior walls of a hollow leg, while the lower edges of said arms engage against lower portions of the same walls.

5. In a caster, the combination of a leg-supporting plate, a frame comprising a transverse top portion and arms at opposite sides thereof, and means for holding said frame above said plate, said top portion being approximately rectangular and said arms being so arranged as to permit the frame to be turned as it is pushed up within 10 a tapered hollow leg of rectangular section, until the corners of said top portion engage the interior walls of the leg, said arms being adapted to engage against interior walls of the leg at points below those 15 engaged by said corners.

6. In a caster, the combination of a leg-supporting plate, a vertical spring-frame retaining member extending centrally from said plate and a spring frame comprising a transverse top portion and arms at opposite sides thereof, said frame being retained in position by said vertical member, and said arms being twisted to position the lower edges thereof in planes which extend at angles to the upper edges thereof.

7. In a caster, the combination of a leg-supporting plate having upturned flanges at its edges, a vertical spring-frame retaining member extending centrally from said 30 plate and a spring frame comprising a trans-

verse top portion and arms at opposite sides thereof, said frame being retained in position by said vertical member, and said arms being twisted so that the lower edges thereof will be parallel to and engage against the inner surfaces of opposite flanges of said plate, when the frame is not inserted in a leg, while the edges of said top portion will be inclined at angles to the planes of said flanges.

8. In a caster, the combination of a leg-supporting plate having a central opening therethrough, a pintle extending upwardly through said opening, and a spring frame having a transverse top portion with arms at opposite sides thereof, said top portion having an opening through which said pintle extends, and said arms being twisted to position the lower edges thereof in planes which extend at angles to the upper edges thereof.

9. In a caster, the combination of a vertical spring-frame-retaining member and a spring frame comprising a transverse top portion and arms at opposite sides thereof, said frame being retained in position by said vertical member, and said arms being twisted to position the lower edges thereof in planes which extend at angles to the upper edges thereof.

Signed at Bridgeport, in the county of Fairfield and State of Conn., this 1st day of August, A. D. 1921.

WALTER F. HEROLD.
